(57) **CLAIM**

We claim the ornamental design for an enteral feeding device, as shown and described.

DESCRIPTION

FIG. 1 is an isometric view of an enteral feeding device showing my new design;

FIG. 2 is another isometric view of the enteral feeding device of FIG. 1;

FIG. 3 is a front view thereof;

FIG. 4 is a rear view thereof;

FIG. 5 is a side view thereof;

FIG. 6 is another side view of the enteral feeding device;

FIG. 7 is a top view of the enteral feeding device; and,

FIG. 8 is a bottom view thereof.

The broken lines in the Figures are for the purposes of showing environment only and form no part of the claimed design.
